UNITED STATES PATENT OFFICE.

ROBERT J. MONTGOMERY AND WEBSTER H. HILL, OF CHICAGO, ILLINOIS, ASSIGNEES
TO SANITAX BRUSH COMPANY, OF CHICAGO, ILLINOIS, A CORPORATION OF ILLINOIS.

BRUSH.

1,013,558.

Specification of Letters Patent.

Patented Jan. 2, 1912.

Application filed February 20, 1911. Serial No. 609,602.

To all whom it may concern:

Be it known that we, ROBERT J. MONTGOMERY and WEBSTER H. HILL, citizens of the United States, residing at Chicago, in the county of Cook and State of Illinois, have invented certain new and useful Improvements Relating to Brushes, of which the following is a specification, reference being had to the accompanying drawings.

10 This invention relates to brushes and more especially to toilet brushes of the character employing a removable bristle-bearing frame whereby such frame may be readily separated from the brush-back to enable it 15 to be more effectually cleaned than it could be if all of the parts of the brush were immovably secured together.

The object of the invention is to provide novel and effective means for detachably securing such bristle-bearing frame in place, and we accomplish this object by the means shown in the drawings and hereinafter specifically described.

That which we believe to be new will be 25 set forth in the claims.

In the drawings:—Figure 1 is a bottom plan view of a hair-brush embodying our improvements, the bristles of the brush being broken away in several places so as to 30 show the fixed and movable prongs or teeth that hold the bristle-bearing frame to the brush-back; Fig. 2 is a top plan view, a portion of the brush-back being broken away to show the operating devices that are located in the chamber in said back; Fig. 3 is 35 a detail, being a vertical longitudinal section taken at line 3—3 of Fig. 2; Fig. 4 is a vertical cross-section taken at line 4—4 of Fig. 2; Fig. 5 is an enlarged detail, being a 40 vertical cross-section taken at line 5—5 of Fig. 2; and Fig. 6 is an enlarged detail, being a vertical cross-section taken at line 6—6 of Fig. 2 and showing the engagement of the stud with the under side of the brush-back whereby the operating mechanism is 45 locked against accidental movement that might release the bristle-bearing frame.

In the several figures of the drawings in which corresponding parts are indicated by 50 like reference characters: 10—11 indicate the brush-back, the same being formed, in the construction shown, of two thin metal plate portions spaced apart and suitably united along their edges,—the numeral 10

indicating the lower plate portion and the 55 numeral 11 the upper plate portion—said plate portions being extended so as to form together a handle 12. In the hollow back or chamber thus formed is located the operating mechanism hereinafter described. 60 The lower plate member 10, in the construction shown, is stamped up so as to provide a large shallow recess in which fits a bristle-bearing frame of any approved construction. The bristle-bearing frame shown is of 65 a well-known construction, made of metal and formed of a series of oval-shaped strips suitably joined together and provided on the under face with a large number of integral hollow plugs 14 in which the bristle 70 bunches 15 are held.

At the forward end of the brush the under face of the hollow brush-back is provided with one or more fixed prongs or teeth 16—two being shown in the drawings, see 75 Fig. 1,—which project inward slightly over the recess in which rests the bristle-bearing frame and which serve to retain the bristle-bearing frame in place at that end of the brush. Turning now to the means employed for further securing such bristle-bearing frame to the brush-back—17 and 19 indicate respectively two arms arranged transversely of the brush and located in the chamber of the hollow back, each of said 80 arms, in the construction shown, resting upon the face of the lower member or plate 10 of said hollow back and bent, as shown, to conform substantially to the stamped shape of such plate member. The outer end 85 portion of each arm is turned to adapt it to project through a suitable small opening cut in the said plate member 10—such projecting ends forming small prongs—indicated respectively by 18 and 20—that are adapted 90 to be moved under the edge of the bristle-bearing frame 13 (see Figs. 1 and 4) and thereby, in connection with the prongs or teeth 16, hold said frame securely in place. To insure the arms 17 and 19 being always 100 capable of being moved back and forth in a straight line and thereby be better adapted to engage the bristle-bearing frame and be disengaged from it, the inner ends of the arms are made to interlock or fit one within 105 the other. This is accomplished by cutting a large straight-sided notch 21 in one arm, the inner end of the other arm being made

so as to fit snugly therein. The arms 17 and 19 are also provided with short slots 22 and 23, respectively, extending lengthwise of the arms, into which respectively project pins 5 24 and 25 secured to the face of the plate member 10. The arm 19 is also provided near its inner end with another short longitudinal slot 26 (see Fig. 2) through which passes a pivot 27 secured to said plate member 10 and upon which is pivotally mounted an operating lever 28. At opposite sides of this pivot 27 and at short distances therefrom the lever is connected by pin-and-slot connections 29 and 30 to the arms 17 and 19 15 respectively. It will be evident that by reason of the construction and arrangement of parts described the arms 17 and 19 will be projected or drawn in simultaneously and uniformly upon the lever 28 being moved, 20 and that accordingly as they are moved in or out the prongs on their ends will engage and hold the bristle-bearing frame or be disengaged therefrom. When the prongs are disengaged from said frame the frame 25 can easily be removed from the brush-back as the forward prongs 16 are not sufficient to hold said frame 13 without the coöperation of the movable prongs 18 and 20. To insert the frame 13 in place all that is necessary to do is to have the lever so positioned as to hold the arms moved outward, slip the forward end of the bristle-bearing frame beneath the stationary prongs 16, press the bristle-bearing frame down into its recess in 30 the face of the brush-back, and then by a movement of the lever draw the arms 17 and 19 inward, which will cause their respective prongs 18 and 20 to engage under the said frame 13.

40 As shown the lever 28 is bent—see Fig. 2—so that its free end may project through a suitable opening in the edge of the brush-back, either in the handle portion 12 or adjacent thereto. Such projecting end is best 45 provided with a slight lip or flange that can be engaged by the user's finger nail to draw the lever out enough to enable it to be grasped. It is advisable that means for locking the lever against accidental movement be provided and to that end we provide 50 on the under face of the lever a stud, as 31, which at its lower end is adapted to project into a small opening 32 cut in the plate member 10. The lever 28, as is best shown 55 in Fig. 3, is bent downward at its outer portion and is to be made of a material having springiness enough to cause the stud to be forced down at all times, and hence when the stud is moved over said opening 32 it 60 will drop therein and the lever will thereby be sufficiently locked to insure its remaining unmoved unless by design of the user. As shown in Fig. 6 we reduce the portion of the stud that enters the opening 32 and also 65 round that portion, the rounding being done

to enable it to be moved more readily out of the opening, as will be readily understood.

What we claim as our invention, and desire to secure by Letters Patent, is—

1. In a brush, the combination with a chambered back and a bristle-holding frame, of movable clamping means located in said back above said frame and adapted to engage said frame.

2. In a brush, the combination with a back comprising an upper and a lower plate connected together and forming a chamber between them, of a bristle-holding frame adapted to be secured to said lower plate 75 member of the frame, and movable clamping means located in said chamber and carried by said lower plate member, said clamping means being adapted to engage said frame.

3. In a brush, the combination with a chambered back and a bristle-holding frame, of movable arms located in said chambered back, the ends of said arms projecting from said back at opposite sides thereof and adapted to engage the edge of said frame, 80 and means for simultaneously moving said arms.

4. In a brush, the combination with a chambered back and a bristle-holding frame, of means at the forward part of the said 95 back for engaging and holding said frame, movable arms located in said chambered back, the ends of said arms projecting from said back at opposite sides thereof and adapted to engage the edge of said frame, 100 and means for simultaneously moving said arms.

5. In a brush, the combination with a chambered back and a bristle-holding frame, of movable arms located in said chambered 105 back, the ends of said arms projecting from said back at opposite sides thereof and adapted to engage the edge of said frame, and an operating lever pivoted to said back and loosely connected at opposite sides of 110 the pivot to said arms.

6. In a brush, the combination with a chambered back and a bristle-holding frame, of movable arms located in said chambered back, the ends of said arms projecting from said back at opposite sides thereof and adapted to engage the edge of said frame, an operating lever pivoted to said back and operatively connected to said arms, and means for locking said lever to the back 115 120 when said arms are in engagement with said frame.

7. In a brush, the combination with a chambered back and a bristle-holding frame, of movable arms located in said chambered back, the ends of said arms projecting from said back at opposite sides thereof and adapted to engage the edge of said frame, an operating lever pivoted to said back and operatively connected to said arms, and 125 130

means for automatically causing a locking engagement of the lever with said back when said lever has been moved to cause the arms to engage and hold said frame.

- 5 8. In a brush, the combination with a chambered back and a bristle-holding frame, of movable arms located in said chambered back, the ends of said arms projecting from said back at opposite sides thereof and 10 adapted to engage the edge of said frame, an operating lever pivoted to said back and operatively connected to said arms, and a stud secured to said lever and adapted to have its free end enter an opening in the 15 back to lock said lever in place.

9. In a brush, the combination with a chambered back and a bristle-holding frame, of movable arms located in said chambered back and projecting therefrom at opposite

sides and adapted to engage the edge of 20 said frame, each of said arms having a longitudinal slot, pins secured to said back and entering said slots, and means for moving said arms.

10. In a brush, the combination with a 25 chambered back and a bristle-holding frame, of movable arms located in said chambered back and projecting therefrom at opposite sides and adapted to engage the edge of 30 said frame, the said arms being movably interlocked with each other at their ends, and means for moving said arms.
